UNITED STATES PATENT OFFICE.

JOHN A. LENTZ, OF PHOENIX, ARIZONA.

DENTAL SHOULDER-CUTTING INSTRUMENT.

Application filed May 31, 1922. Serial No. 564,790.

To all whom it may concern:

Be it known that I, JOHN A. LENTZ, a citizen of the United States, and a resident of Phoenix, county of Maricopa, and State of Arizona, have invented a new and useful Dental Shoulder-Cutting Instrument, of which the following is a specification.

The present invention relates to improvements in dental instruments and has particular reference to a tool for cutting a shoulder around a tooth to be crowned. The principal object of the invention is to provide means in connection with this tool for shielding the gum and the neighboring teeth from the cutting tool, which in this case is a rotary burr and for limiting at the same time the lateral as well as the longitudinal cutting action of the tool. Further objects and advantages will appear as the specification proceeds.

The preferred form of my device is illustrated in the accompanying drawing in which Figure 1 shows my device attached to a straight dental engine hand-piece; Figure 2, the same device attached to a bent hand piece; Figure 3 an enlarged detail view of a sheath used in connection with the cutting burr; Figure 4 a section through the same along line 4—4 of Figure 3; Figure 5 a cross-section through the same along line 5—5 of Figure 3; Figure 6 a detail view of an upper tooth as it usually appears before the cutting operation is commenced; Figure 7 a detail view of the tooth having been prepared for the operation with my instrument shown in place; Figure 8 a detail view of the same tooth after the operation has been performed and Figures 9 to 16 side and end elevations of various forms of cutting burrs. While only one principal form of sheath has been shown in this drawing it should be understood that various changes or modifications may be made within the scope of the claims hereto attached without departing from the spirit of the invention.

The dental engine hand-piece (1) shown in Figure 1 is of the usual form comprising a housing (2) and a shaft (3) rotatably supported therein and driven by any suitable means not shown in the drawing. The shaft (3) drives the burr of which various forms are shown in Figures 9 to 16. The burr (4) shown in Figures 9 and 10 is an ordinary smooth fissure burr cutting on the end and on the side adapted to cut both laterally and longitudinally and leaving a smooth surface.

Figure 11 shows a cross cut fissure burr (6) adapted to be used for very hard tooth structure, such as enamel. Figures 13 and 14 show a smooth sided burr (7) adapted to cut longitudinally and Figure 15 a smooth end burr (8) adapted to cut laterally only. Any of these burrs may be used in connection with my device. The invention resides principally in the sheath (11) shown in detail in Figures 3, 4 and 5. This sheath has a tapered base (12) adapted to slide over the end (13) of the housing (2) and to be secured there in any suitable manner. From this base extends a cylindrical portion (14) having a longitudinal section (16) cut away so as to surround the burr substantially on three sides by allowing the same to protrude on one side which latter side will be referred to as the active side of the burr. The cylindrical portion (14) thus provides a sheath for the burr protecting the gum as well as neighboring teeth. It will be noted from Figure 7 that the cut in the sheath slants away from the tooth toward its outer end so as to allow a larger portion of the burr to be exposed at the end of the burr than near the base.

As a mere protection for the gum and the surrounding teeth and the neighboring teeth it is sufficient if the sheath is co-extensive in length with the burr but I preferably allow the sheath to extend beyond the burr as shown at (17) and to come to a point (18) lying on or near the axial center line of the burr. The function of the extension is to prevent the burr from penetrating the tooth laterally beyond a desired depth, it serving at the same time to cause the shoulder to substantially follow the outlines of the circumference of the tooth. A step or indent (19) is provided in the sheath substantially on a line with the end of the burr which step is adapted to ride on the shoulder during the cutting operation so as to limit the longitudinal cutting of the tooth beyond the desired depth.

The sheath is provided in its back with a slot (21) or suitable perforations allowing the débris to be cleared away.

The operation of the device will be readily understood particularly with the aid of the Figures 6 to 8 in the drawing. Figure 6 shows the tooth in its normal form before it is worked on. By the use of tools not described in this specification it is re-

duced so as to present a tapered end as shown in dotted lines (20) in Figure 6. Now my tool is applied as shown in Figure 7 and the rotating burr allowed to engage the tooth while the sheath prevents the burr from coming in contact with the gum or with any neighboring teeth. The final shape of the shoulder may be somewhat as shown in Figure 8, the point (18) of the sheath engaging the tooth above the shoulder in the case of an upper tooth and limiting thereby the lateral penetration of the burr. After the shoulder has been started the step (19) in the sheath will ride on the same and thereby limit the longitudinal penetration of the burr.

It will be understood from the foregoing description that the sheath as such will be operative and perform an important function without the point (18) and the step (19) and I wish to be protected on this point by itself, as well as on the other features.

The form shown in Figure 2 varies from that shown in Figure 1 only in so far as it has been adapted to be used with a bent hand-piece. It will be seen that for this purpose I provide a bearing (22) inside the housing engaging the same threadedly and provided with an external flange (23) lying on the outside of the housing (24) for the shaft (26). The base (21) of my sheath is placed over the flange (23) and may be secured thereto in any suitable manner.

I claim:

1. A dental instrument for cutting a shoulder into a tooth comprising a rotary burr and a sheath for the same leaving one

side of the burr free for lateral engagement with the tooth at any desired elevation.

2. A dental instrument for cutting a shoulder into a tooth comprising a rotary burr and a sheath for the same leaving one side of the burr free for lateral engagement with the tooth at any desired elevation, the sheath extending beyond the burr for laterally limiting the depth of the cut.

3. A dental instrument for cutting a shoulder into a tooth comprising a rotary burr and a sheath for the same leaving one side of the burr free for lateral engagement with the tooth at any desired elevation, the sheath extending beyond the burr for laterally limiting the depth of the cut, and a step being formed in the sheath on a level with the end of the burr adapted to ride on the shoulder for limiting the cut longitudinally.

4. A dental instrument for cutting a shoulder into a tooth comprising a rotary burr and a sheath for the same leaving one side of the burr free for lateral engagement with the tooth at any desired elevation, with the shield formed to ride on the shoulder after the latter has been started for limiting the cut longitudinally.

5. A dental instrument for cutting a shoulder into a tooth comprising a rotary burr and a sheath for the same leaving one side of the burr free for lateral engagement with the tooth at any desired elevation, with an opening in the sheath allowing the débris to pass therethrough.

JOHN A. LENTZ.
